Primary Examiner—Sandra Snapp(74) Attorney, Agent, or Firm—Fish & Neave IP Group Ropes & Gray LLP(57) CLAIM

I claim the ornamental design for a seat, as shown and described.

DESCRIPTION

FIG. 1 is a front view of a first embodiment of my new seat design in the form of a sofa;

FIG. 2 is a side view thereof;

FIG. 3 is a perspective view thereof;

FIG. 4 is a rear view thereof;

FIG. 5 is a side view thereof;

FIG. 6 is a top view thereof;

FIG. 7 is a front view of a second embodiment of the new seat design in the form of a chair;

FIG. 8 is a side view thereof;

FIG. 9 is a perspective view thereof;

FIG. 10 is a rear view thereof;

FIG. 11 is a side view thereof;

FIG. 12 is a top view thereof; and,

FIG. 13 is a front perspective view thereof with the seat shown in a reclined position.

The dashed lines in the drawings are understood to represent stitching. The dot-dash lines are shown for illustration only and form no part of the claimed design.
